Fig. 5

FIG. 1 is a front perspective view taken from one side of a combination bathtub and shower stall embodying my new design;

FIG. 2 is another front perspective view taken from the side opposite that shown in FIG. 1;

FIG. 3 is a top plan view thereof;

FIG. 4 is a front elevation thereof; and

FIG. 5 is an elevation taken from the side shown in FIG. 1.

The broken line representation of a spout in FIG. 2 is for purposes of illustration only.

I claim:

The ornamental design for a combination bathtub and shower stall, substantially as shown and described.
